ELECTRIC SIGNALING SYSTEM

John Gordon Gordon-Wright, Liverpool, England, assignor to Automatic Telephone & Electric Company Limited, Liverpool, England, a British company

Application May 12, 1948, Serial No. 26,597
In Great Britain June 14, 1947

2 Claims. (Cl. 177—353)

1

The present invention relates to electrical signalling systems and is more particularly concerned with systems involving the application of high frequency signals to electric supply mains for the purpose of operating a number of responding devices connected thereto at different points. By high frequency is meant high compared with the frequency of the supply and in practice a frequency within the audio range is found most appropriate. Systems of this type already find considerable application for the control of street lighting and may also be used for effecting tariff change or some form of load control.

Such systems have sometimes not proved perfectly reliable because the applied signal has been masked or mutilated by surges or other parasitics from which electric supply systems are never entirely free. These parasitics may be due to switching operations or possibly to signals of similar type spilling over from adjacent networks. It is highly desirable that in the event of any failure for this reason the operator should have some means of knowing that the transmission has not been effective so that suitable steps may be taken to ensure that the required switching operation is in fact performed. The chief object of the invention is to provide improved arrangements for actually testing whether the signal has been properly applied to the network and whether the conditions then existing were such as to enable it to produce its proper effect.

According to the invention, in an electrical signalling system employing audio frequency currents superimposed on electric supply mains for effecting switching operations at a plurality of remote points, supervisory equipment associated with the signal transmitting equipment includes a unit similar to those employed at the remote points for responding to signals, the supervisory equipment being arranged to control the signal transmitting equipment so as to cause the transmission of a signal to be repeated if it fails to produce satisfactory operation of the supervisory unit.

The invention will be better understood from the following description of one method of carrying it into effect, reference being had to the accompanying drawing which shows by means of a circuit diagram the application of the invention to a system using signals of the so-called cadence type. By this is meant that the same signalling frequency is employed for a number of different signals and the necessary distinction is made by applying the signals at different cadences or rhythms to which the responding devices are mechanically tuned. The arrangement contemplated is that the audio-frequency signalling currents are injected on to the phase leads L₁, L₂, L₃ of a low tension portion of the network and

2

the responding units are connected between any one of these phase leads and the neutral conductor. In the drawing, connection to the live lead is represented by the letter L and to the neutral lead by the letter N and by way of example two responding units R₁ and R₂ for producing the desired switching operations are shown connected between the neutral N and the phase leads L₁ and L₂ respectively. These include relays of the oscillating magnet type sometimes known as galvanometer relays which are mechanically tuned to the different cadences and when energised at suitable intervals build up a swing sufficient to operate their contacts.

15 It is found that in suitable circumstances application of the signalling currents to one low tension network will result in the transmission of these currents over the high tension network to other low tension networks also. This method of injection thus avoids the special insulation difficulties which arise if injection is made direct to the high tension network in order to be effective over a plurality of low tension networks connected thereto.

25 The manually operable selector switches S_{A1} and S_{A2} are coupled together so that they always occupy corresponding positions and they are shown resting on unwired contacts which may be the normal position. The remaining

30 contacts of switch S_{A1} extend to the contacts of galvanometer relays in the signal rhythm controller SRC for controlling rhythms which may be injected into the alternating current supply network, while the remaining contacts of switch

35 S_{A2} extend to corresponding supervisory responding devices such as SR which are connected to the network at the transmitting point and are similar to the responding devices which are to effect the required switching operations.

40 If for example the switch arms are set on contacts 3, the rhythm relevant to a particular remote controlling operation to be effected, say the switching on of street lights, is selected over switch S_{A1}, and the lead S_{LA} whose condition

45 is subsequently indicative of the operation or non-operation of the supervisory relay SR in response to the injected signal is selected over switch S_{A2}.

To initiate the transmission of the signal selected, the push button switch KTS is closed momentarily, thereby operating relay A which locks up over its contacts A₁, at contacts A₂ operates relay G and at contacts A₃ and A₄ closes points in the paths to switches S_{A1} and S_{A2} respectively. Relay G upon operating, at contacts G₁ prepares a locking circuit for relay F, at contacts G₂ energises the motor starter of the voice frequency motor alternator VFMA which proceeds to run up to speed, at contacts G₃ starts the synchronous motor ST which is used for signal

timing purposes and at contacts G4 and G5 connects direct current positive and negative to the signal rhythm controller SRC. The synchronous motor ST drives cams which are arranged to actuate contacts ST1, ST2 and ST3 which are operated cyclically. It will be assumed that one cycle of operations is executed in sixty seconds and, by way of example, contacts ST1 close six seconds after the start and remain closed for the remainder of the cycle, contacts ST2 close twelve seconds after ST1 and remain closed for eighteen seconds and contacts ST3 close for two seconds six seconds before the end of the cycle. Thus the closed periods are: ST1, 6-60; ST2, 18-36; and ST3, 54-56.

The direct current connected up by relay G to the signal rhythm controller is applied simultaneously to relay WG, the operation of which is slightly delayed since it is of the slow-to-operate type, and to the lower coils of the galvanometer relays GA, GB and GC in series. When the coils of the relays are thus energised steadily, the magnets are deflected so as to open contacts GA1, GB1 and GC1; contacts GB1 and GC1 remain ineffectual however since it is assumed that the arm of switch SA1 is set on contact 3. When relay WG operates, the lower galvanometer relay coils are disconnected to permit the magnets to swing in the reverse direction and their respective contacts then close. When contacts GA1 close, the upper coils of the relays are energised momentarily until the operation of relay XG and the oscillating magnet of relay GA is again deflected in such a direction as to open its contacts whereupon relay XG releases. It will be apparent that the moving system of relay GA will proceed to oscillate at its natural frequency and that relay XG will operate and release in synchronism.

Contactors CA1 and CA2 are normally closed so that the output of the voice frequency motor alternator VFMA is normally short-circuited and is consequently not initially transmitted over leads L1, L2 and L3 to the supply network. However, eighteen seconds after the start of the signalling cycle contacts ST2 close to cause relay H to operate and release in synchronism with contacts XG2 whereupon the actuating coil CA associated with the contactors is also alternately energised and de-energised to actuate the contactors accordingly. By this time the motor alternator has run up to speed so that each time the contactors open, its output at an appropriate frequency is extended over the resonant circuits including inductor IA and capacitor QA, inductor IB and capacitor QB and inductor IC and capacitor QC to leads L1, L2 and L3 whence it is applied to the supply network. In this manner regular pulses of voice frequency current are injected into the network, as selected by the switch SA1, for the eighteen seconds during which contacts ST2 remain closed.

It will be apparent that had the selector switch been set to a different position, the rhythm of the pulses would have been determined by the frequency of oscillation of the galvanometer relay associated with that position.

As already mentioned a number of supervisory responding units such as SR, each of which conveniently embodies two galvanometer relay elements individually tuned to respond to the pulses derived from two corresponding transmitting galvanometer relays, are connected to live and neutral conductors of the supply network at the transmitting point.

If the cadence signal is injected correctly into

the network and is not appreciably mutilated or masked, the appropriate galvanometer relay of the supervisory responding unit SR will be set in operation and will close its contacts. The voice frequency signal superposed on the supply is applied to the resonant circuit comprising capacitor QD and inductor ID which is loosely coupled with a second resonant stage comprising inductor IE and capacitor QE to provide a resonant band pass filter. The signal is rectified by the rectifier bridge RB and extended to the local circuit containing the series connected galvanometer relays "on" and "off." It will be assumed that relay "on" is tuned to the rhythm of the signal used for switching on street lights while relay "off" is tuned to the rhythm for switching off the street lights. The oscillating magnets of both relays are deflected slightly due to the initial D. C. pulse but only relay "on" will beat with the rhythm of the signal and eventually after a plurality of pulses close its contacts "on" whereupon the latching relay S is operated over its left-hand coil to close contacts S1. These contacts then complete a circuit over lead SLA to relay B which operates and at contacts B1 prepares a circuit for relay D, at contacts B2 opens a point in the circuit for relay E and at contacts B3 completes a locking circuit for itself and lights lamp LSR to indicate that the signal has been correctly received.

When the contacts ST3 subsequently close after 54 seconds, relay D operates, locks up at contacts D1 and at contacts D2 releases relay A which in turn releases relay G. The interaction of relays XG and GA is then stopped and relay WG also releases. Relay D releases when contacts ST3 open and when contacts ST1 open at the end of the cycle the motor ST comes to rest. The lamp indication may now be cancelled and relay B released by operating the push button KCSR momentarily so that the circuit is fully restored to normal.

When it is required later to switch the street lights off, the selector switches SA1 and SA2 are set on contacts 5 and the push button switch KTS is operated. The circuit functions in substantially the same manner as before but in this case pulse signals appropriate to the galvanometer relay GB are injected into the network and the galvanometer relay "off" embodied in the supervisory responding unit SR operates so that the right-hand coil of the latching relay S is energised and contacts S1 are restored to the position shown. A circuit is then completed over lead SLB and switch SA2 to operate relay B which functions as before.

A further function of the circuit is to perform automatic remote control operations at predetermined times under control of a time switch. The signals appropriate to such operations are injected and supervised independently of the selector switches but otherwise the circuit functions as previously described.

In this case the time switch TS assumed to be driven by a synchronous motor is set to close its contacts TS1 at a predetermined time and when this occurs relay TA operates, locks dependent upon relay D and performs the same functions as relay A. However, whereas contacts A3 extend a positive battery connection to the coils of galvanometer relays GA, GB and GC by way of selector switch SA1, contacts TA2 extend the connection direct to those relays. Similarly contacts TA3 connect relay B direct to the appropriate switched live lead of the appropriate

supervisory responding unit. It will be understood that the circuits could readily be arranged to prevent the sending of signals by manual control while the time switch control was effective or vice versa and this might be desirable in practice.

Assuming now that switching on of the street lights is again required to be effected but that during the injection mutilation of the signal occurs to such an extent that the relay "on" in the supervisory responding unit does not operate effectively. Consequently contacts S1 are not changed over and relay B fails to operate. In this case when contacts ST3 close, relay E operates over normal contacts B2 and thereupon at contacts E1 provides a locking circuit for itself, at contacts E2 prevents the operation of relay D and at contacts E3 operates relay C. Relay C locks at contacts C1, at contacts C2 operates relay F, and at contacts C3 completes a circuit for the signal failure alarm bell AB. Relay F locks up at contacts F1, at contacts F2 opens the initial circuit for relay E and at contacts F3 prepares a circuit for relay D. Relay E releases when contacts ST3 open. The audible alarm may be cancelled at any time by operating the push button switch KCA momentarily to release relay C.

Since relay D is not operated, relays A, G, F and WG remain operated so that the motor ST continues to run and the signal sequence is repeated as before when contacts ST2 close. If this second injection is successful, as will generally be the case since it is improbable that mutilation or masking will be of so long a duration as to prevent it, relay B subsequently operates to indicate the correct response of the supervisory equipment as before. Relay B also operates relay D which results in the release of relays A, G, WG and F. Finally relay D releases when contacts ST3 open. The indication lamp LSR may be extinguished by operating switch KCSR and the circuit is then fully restored to normal.

If however the second injection also is unsuccessful, relay B again remains inoperative and lamp LSR again fails to light. When contacts ST3 close, relay D operates over contacts E2 and F3 and brings down relays A, G, WG and F assuming that relay C has already been released by operation of key KCA. A circuit is then again completed for relay E which in turn re-operates relay C so that the alarm is again sounded. If relay C has not previously been released, it maintains relay F operated so that re-energisation of relay E is not possible. Relay D releases when contacts ST3 open and no further injection operation takes place since relays A and G are de-energised. Clearly there would be no difficulty in arranging for the injection operation to be repeated until successful if such an arrangement were found to serve any useful purpose but in practice it is likely that if two successive injections have been unsuccessful some more serious trouble has developed which will require investigation by the operator.

It may be mentioned that the arrangement shown whereby the coils of the galvanometer relays in the equipment SRC are connected in series is a convenient one in practice but the coils could also be connected separately to the contacts of the switch SAI, if necessary in series with suitable resistors. Moreover the provision of two coils for each relay is a convenient arrangement to ensure an adequate initial swing

but the effect could also be produced with a single coil.

The invention therefore provides a simple arrangement for improving the operation of equipment for signalling over electric supply mains whereby greater reliability and convenience are secured without any appreciable increase in the amount of equipment required.

I claim:

1. An electrical signalling arrangement for operating a plurality of switching devices connected to electric supply mains at separated points and responsive respectively to signalling currents of audio frequency of different cadences superimposed on said mains comprising a source of signalling current located at a control station, means at said control station for applying said source to said supply mains at different cadences, a manually operable rotary selecting switch, a first wiper on said switch arranged to select the particular cadence at which signalling current is applied, a plurality of switching devices connected to said supply mains at said control station and responsive respectively to the different cadences at which signalling current may be connected to said mains in accordance with circuits completed over said first wiper, contacts controlled by said switching devices connected to the bank contacts co-operating with a second wiper of said switch and means connected to said second wiper for terminating the application of said signalling current to said mains after a predetermined period if the switching device corresponding to the desired cadence has been operated.

2. An electrical signalling arrangement for operating a plurality of switching devices connected to electric supply mains at separated points and responsive to periodic currents of audio frequency superimposed on said mains comprising a source of signalling current located at a control station, means at said control station for applying to said supply mains a signal of predetermined cadence, a manually operable key and a time switch each arranged to render said means effective, a manually operable rotary switch for selecting the cadence of said signal by circuits completed over a first wiper of said switch, a circuit controlled by said time switch independently of said manually operable switch for determining the cadence of said signal, a plurality of switching devices responsive respectively to signals of different predetermined cadences and individually connected to the bank contacts associated with a second wiper of said switch, a further switching device responsive to signals of the cadence determined by said time switch and means controlled by each of said switching devices for terminating the application of said signal after a predetermined period.
